RAILWAY SIGNAL CONTROL SYSTEM

James H. Butridge, Kankakee, and William H. Claus, Downers Grove, Ill., assignors to The Union Switch and Signal Company, Swissvale, Pa., a corporation of Pennsylvania

Application October 6, 1948, Serial No. 53,112

7 Claims. (Cl. 246—33)

1

Our invention relates to a railway signal control system, and particularly to a control system for signals for governing traffic movements in opposite directions over a stretch of single track railway.

In a railway signaling system of the well-known absolute permissive block type for a stretch of single track railway which is provided with passing sidings spaced along the single track, two pairs of head block signals each comprising an entering and a leaving signal are commonly employed for each passing siding for governing traffic movements in opposite directions, and are placed one pair adjacent each end of each passing siding. One or more pairs of intermediate signals for governing traffic movements in opposite directions are also commonly employed between consecutive passing sidings. Protection for opposing traffic movements between passing sidings is obtained by suitable arrangement of the intermediate signals or by overlapping controls for the opposing leaving head block signals.

One feature of our invention is the provision of an overlapping control arrangement for opposing head block signals, in which coded track circuits are employed for the stretch of single track between each two consecutive passing sidings, and non-coded track circuits are employed between the pairs of head block signals at the two ends of each passing siding.

Another feature of our invention, in an overlapping control arrangement for opposing head block signals in which coded track circuits are employed between passing sidings, is the requirement of only two line control conductors between each two consecutive passing sidings, and four line control conductors between the pairs of head block signals at the two ends of each passing siding.

An advantage of controlling the signals between passing sidings of a single track stretch partially by coded track circuits and partially by direct current line circuits, in our invention, is that, because of using coded track circuits for only one direction of traffic movements, it has been possible to keep the track circuits uncomplicated, although three different code frequencies are employed, and at the same time, because of using the coded track circuits, only two line control conductors are necessary.

We shall describe one form of apparatus embodying our invention, and shall then point out the novel features thereof in claims.

The accompanying drawings, Figs. 1a and 1b,

2

when placed end to end with Fig. 1a on the left, constitute a diagrammatic view showing one form of apparatus embodying our invention, in which a stretch of single track railway is provided with 5 passing sidings spaced along the single track railway, and in which two pairs of head block signals are employed for each passing siding and are placed one pair adjacent each end of each passing siding, and one pair of intermediate signals is employed between consecutive passing sidings for governing traffic movements in opposite directions; and in which coded track circuits are employed for the stretch of single track between each two consecutive passing sidings, 15 and non-coded track circuits are employed between the pairs of head block signals at the two ends of each passing siding, for providing an overlapping control arrangement for opposing entering head block signals and for opposing leaving head block signals.

Similar reference characters refer to similar parts in each of the drawings.

In each of the drawings, the contacts operated by the various relays or other devices are 25 identified by numbers, each such number having a distinguishing prefix, from which it is separated by a dash, when the associated contact is shown apart from the relay by which it is operated. The prefix for each of these contact numbers comprises the reference character for the 30 respective relay by which the associated contact is operated. For example, contact 6HDP—49, shown in the lower right-hand portion of Fig. 1a, in a pickup circuit for relay 5SR, is identified by the number 49 separated by a dash from the prefix 6HDP which is the reference character for relay 6HDP by which this contact is operated.

Referring further to the drawings, a portion 35 of a single track railway is shown provided with passing sidings X and W. In order to simplify the drawings, each track, comprising two parallel series of track rails, is represented by a single line.

The portion of the single track railway shown 40 in the drawings is divided by insulated joints 12 to form sections, each of which is designated by the reference character T preceded by a distinguishing numerical prefix.

Each of the track sections 2T and 3T between 45 the two pairs of head block signals at siding X, and each of the track sections 8T and 9T between the two pairs of head block signals at siding W is provided with a non-coded track circuit including a suitable source of current, such as a battery 13, connected across the rails adjacent

one end of the section, and a track relay, designated by the reference character TR with a distinguishing prefix corresponding to that in the reference character for its section, connected across the rails adjacent the opposite end of the section.

Each of the sections 5T and 6T between the two consecutive passing sidings X and W is provided with a coded track circuit including a suitable source of current, such as a battery 14, connected across the rails adjacent one end of the section through a contact of a polar biased code repeating relay, and a track relay of the polar biased code following type, designated by the reference character TR with a distinguishing prefix corresponding to that in the reference character for its section, connected across the rails adjacent the opposite end of the section. A floating track relay of the polar biased code following type is also connected across the rails of each of the sections 5T and 6T adjacent its battery 14. The floating relays are designated by the reference characters 5ATR and 6ATR, respectively.

Each of the sections 0T and 11T, shown at the left-hand end of Fig. 1a, and at the right-hand end of Fig. 1b, respectively, is also provided with a coded track circuit including a suitable source of current, such as a battery 14, connected across the rails adjacent one end of the section through a coding contact. Floating track relays 0ATR and 11ATR of the polar biased code following type are also connected across the rails of sections 0T and 11T, respectively, adjacent the corresponding batteries 14. It is to be understood that in an actual installation of a railway signal control system embodying applicants' invention, a track relay of the polar biased code following type would also be connected across the rails adjacent the opposite end of each of the sections 0T and 11T, similarly to relays 6TR and 5TR of sections 6T and 5T, respectively. It is also to be understood that, in an actual installation embodying applicants' invention, the coding contacts through which batteries 14 are connected across the rails of sections 0T and 11T, would be operated by polar biased code repeating relays controlled similarly to relays 6CTP and 5CTP, instead of being operated directly by a code transmitter 180CT.

Decoding relays 5Afp and 5Abp are controlled by relay 5ATR. Each of these relays is made slow releasing, by a resistor r connected in multiple with its winding, so that each of these relays maintains its front contact closed during the open periods of contact 31 of relay 5ATR at its front and back points through which these relays are controlled. Relays 6Afp and 6Abp are controlled by relay 6ATR similarly to the manner in which relays 5Abp and 5Afp are controlled by relay 5ATR. Relays 0Afp and 0Abp are controlled by relay 0ATR, and relays 11Afp and 11Abp are controlled by relay 11ATR similarly to the manner in which relays 5Abp and 5Afp are controlled by relay 5ATR.

Adjacent each end of each of the passing sidings is a pair of head block signals for governing traffic movements in opposite directions. Signals 1S, 4S, 7S, and 10S which govern traffic movements away from the passing sidings are known as leaving signals, whereas signals 2S, 3S, 8S, and 9S which govern traffic movements toward the passing sidings are known as entering signals. One pair of intermediate signals, designated by the reference characters 5S and 6S, governs

traffic movements in opposite directions between the two consecutive passing sidings. Signals 2S, 4S, 6S, 8S, and 10S govern traffic movements toward the right, as shown in the drawings, which we shall assume is the eastbound direction, whereas signals 1S, 3S, 5S, 7S, and 9S govern traffic movements in the opposite or westbound direction. The signals may be of any suitable design such, for example, as the searchlight type shown in the drawings, each of which comprises a lamp, not shown, and a mechanism designated by the reference character m with a prefix corresponding to the prefix in the reference character for its signal.

15 Two circuit controller contacts designated by the reference characters 15 and 16, are operated in conjunction with each signal mechanism m . Each of the contacts 15 is closed at its front point, designated by the reference character G, when its signal mechanism is in the clear position, and becomes closed at its back point, designated by the reference character R-Y, when its signal mechanism is operated to the caution or the stop position. Each of the contacts 16 is normally closed at its back point, designated by the reference character R-G, while its signal mechanism is in the clear or the stop position, and becomes closed at a front point, designated by the reference character Y, when its signal mechanism is operated to the caution position.

As shown for signals 3S and 8S, contact 15 of each entering signal, in the clear position, controls a clear signal repeater relay, designated by the reference character DP with a prefix which is the same as the prefix in the reference character for its signal. As also shown for signals 3S and 8S, a clear or caution signal repeater slow release relay, designated by the reference character HDP with a prefix corresponding to that of its signal, is controlled by contacts 15 and 16 of each entering signal and by the associated clear repeater relay DP. A clear or caution signal repeater slow pick-up and slow release relay, designated by the reference character HDP, with a prefix corresponding to that in the reference character for each leaving signal and for each intermediate signal, is controlled by contacts 15 and 16 of the corresponding leaving or intermediate signal.

40 45 50 55 60 65 A polar biased code repeating relay 5CTP shown in the lower left hand end of Fig. 1a, is selectively controlled by signal repeater relays 3DP and 3HDP to be energized by current of one of three different codes such, for example, as codes having frequencies of 75, 120, or 180 times per minute. Current of these different codes is provided by interruption of current from a suitable source, having terminals B and N, through contacts of code transmitters designated by the reference characters 75CT, 120CT, and 180CT, respectively.

As is well known, the point of arrival of a train at which a floater track relay releases after the train enters the associated track section at the opposite end is variable. Each of the entering signals in applicants' arrangement is controlled in part by the floating track relay which is adjacent the opposite entering signal, and is therefore provided with a variable overlap control.

65 70 75 At the intermediate signal location, a signal slow pick-up and slow release relay, designated by the reference character 5HR, is energized by current from the secondary winding n of a decoding transformer 5F when current of any one

of the three codes is supplied to the primary winding y of transformer 5F in response to the control of relay 5TR by current of a corresponding code received from track section 5T. A decoding relay 5DRB is selectively controlled through a resonant decoding unit 120DU so as to be operated only by current of 120 code supplied in response to operation of relay 5TR. A second decoding relay 5DRA is controlled through a second resonant decoding unit 180DU so as to be operated only by current of 180 code supplied in response to operation of relay 5TR.

A pole-changer slow release relay 5PC is controlled by front contacts of relays 5DRA and 5DRB to be energized when either of these two decoding relays is energized.

An arc suppressor arrangement, designated by the reference character SU, is employed in conjunction with circuits controlled by contact 24 of relay 5TR, and a similar arc suppressor arrangement SU is employed in conjunction with circuits controlled by contact 24 of relay 6TR.

Mechanism 5m of signal 5S is controlled by relays 5HR and 5DRA to be operated to the clear position only when relay 5TR is energized by current of 180 code received from section 5T, and to be operated to the caution position when relay 5TR is energized by current of 75 or 120 code received from section 5T.

Relays 6HR, 6DRB and 6DRA are controlled by relay 6TR similarly to the manner in which relays 5HR, 5DRB and 5DRA, respectively, are controlled by relay 5TR as just described. Relay 6PC is also controlled similarly to relay 5PC, and mechanism 6m of signal 6S is controlled similarly to mechanism 5m of signal 5S.

A directional stick relay, designated by the reference character 5SR, is controlled to become energized when a westbound train deenergizes relay 5HR upon entering section 5T, and is then controlled to remain energized as long as relay 5HDP remains deenergized. A second directional stick relay, designated by the reference character 6SR, is controlled by eastbound traffic movements similarly to the manner in which relay 5SR is controlled by westbound traffic movements.

Mechanism 7m of leaving head block signal 7S is controlled by relay 5PC to be operated to the clear position only when relay 5PC is energized. As previously described, relay 5PC is energized only when current of 120 or 180 code is received by relay 5TR from section 5T, that is, when signal 3S is controlled to display either the clear or the caution indication. Mechanism 4m of leaving head block signal 4S is controlled similarly to mechanism 7m of signal 7S.

Having described, in general, the arrangement and control of the apparatus shown by the accompanying drawings, we shall now describe, in detail, its operation.

As shown in the drawings, all parts of the apparatus are in the normal condition, that is, each signal mechanism m is controlled for displaying a clear indication; all track sections are unoccupied, and hence all track relays are energized; the current by which the code following track relays 5TR, 6TR, 5ATR, 6ATR, 6ATR and 11ATR are energized is coded at the 180 frequency; the relays 3DP, 8DP, 1HDP, 3HDP, 4HDP, 5HDP, 6HDP, 7HDP, 8HDP, 10HDP, 5HR, 5PC, 6HR, and 6PC, and code transmitters 180CT, 120CT, and 75CT are energized; each of the relays 0AFP, 0ABP, 5AFP, 5ABP, 5DRA, 6DRA, 6ABP, 6AFP, 11ABP, 11AFP, 5CTP and 6CTP is

energized by current of 180 code; each of the signal mechanisms m is energized by current of normal polarity; and each of the relays 5DRB, 6DRB, 5SR and 6SR is deenergized.

5 The circuit by which relay 3DP is energized passes from terminal B, through the front point of contact 15 of signal 3S, and the winding of relay 3DP to terminal N. Relay 3HDP is energized by a circuit passing from terminal B, through contact 17 of relay 3DP, and the winding of relay 3HDP to terminal N. Relays 8DP and 8HDP are energized similarly to relays 3DP and 3HDP, respectively, as just described.

Relay 1HDP is energized by a circuit passing from terminal B, through the front point of contact 15 of signal 1S, and the winding of relay 1HDP to terminal N. Relays 4HDP, 5HDP, 6HDP, 7HDP, and 10HDP are energized by circuits which are similar to the circuit traced for relay 1HDP.

Each of the code transmitters 180CT, 120CT, and 75CT is connected directly across terminals B and N, and is therefore constantly energized. Each code transmitter 180CT, therefore, repeatedly opens and closes its contact 18 at a frequency of 180 times per minute. Each of the code transmitters 120CT repeatedly opens and closes its contact 19 at a frequency of 120 times per minute, and each of the code transmitters 75CT repeatedly opens and closes its contact 20 at a frequency of 75 times per minute.

Relay 5CTP is energized by coded current of the 180 frequency passing from terminal B, through contact 18 of a code transmitter 180CT, from point of contact 22 of relay 3DP, and the winding of relay 5CTP in multiple with a regulating resistor t to terminal N. Contact 5CTP-23 of relay 5CTP therefore repeatedly closes alternately at its front and back points 180 times per minute.

Current of the 180 code is therefore supplied to section 5T from a battery 14, through the front point of contact 5CTP-23. Relay 6CTP is energized similarly to relay 5CTP, and therefore current of the 180 code is also supplied to section 6T from a battery 14 through the front point of contact 6CTP-23.

Relay 5TR is energized by current of the 180 code received from section 5T. Current is therefore supplied from terminal B, through contact 24 of relay 5TR to primary winding y of decoding transformer 5F repeatedly in opposite directions at a frequency of 180 times per minute. The current thereby generated in secondary winding n of transformer 5F is rectified by a contact 25 of relay 5TR for energizing relay 5HR in multiple with a resistor r which makes relay 5HR slow in releasing. Relay 5DRB, on account of being controlled through a 120 decoding unit 120DU, does not respond to the current of 180 frequency supplied through contact 24 of relay 5TR, but relay 5DRA, on account of being controlled through a 180 decoding unit 180DU, closes its front contacts in response to the current of 180

frequency supplied through contact 24 of relay 5TR. Relay 5PC is therefore energized by a circuit passing from terminal B, through contact 26 of relay 5DRA, and the winding of relay 5PC to terminal N. Relays 6TR, 6HR, 6DRA, and 6PC are energized similarly to relays 5TR, 5HR, 5DRA, and 5PC as just described.

With relays 5DRA and 5HR energized, the mechanism 5m of signal 5S is retained in the clear position by a circuit of normal polarity passing from terminal B, through the front point of

contact 28 of relay 5DRA, contact 29 of relay 5HR, mechanism 5m, and the front point of contact 30 of relay 5DRA, to terminal N. Signal mechanism 6m is energized similarly to mechanism 5m.

Mechanism 4m of signal 4S is energized by current of normal polarity for retaining mechanism 4m in its clear position by a circuit passing from terminal B, through the front point of contact 6PC-31, front point of contact 6HDP-32, mechanism 4m, contact 33 of relay 5SR, contact 34 of relay 5HR, and front points of contacts 6HDP-35 and 6PC-36 to terminal N. Mechanism 7m of signal 7S is energized similarly to mechanism 4m.

Floating track relay 5ATR is energized by current of 180 code supplied to section 5T by battery 14 through the front point of contact 5CTP-23, and therefore contact 37 of relay 5ATR is repeatedly closed alternately at its front and back points at a frequency of 180 times per minute. Relay 5Afp is repeatedly energized by pulses of current passing from terminal B, through the front point of contact 37 of relay 5ATR, and the winding of relay 5Afp in multiple with a resistor r to terminal N. Relay 5Afp is made slow releasing by resistor r connected in multiple with its winding, and therefore its contact 38 remains closed during the open periods of contact 37 of relay 5ATR at its front point. Relay 5ABP is energized by pulses of current passing from terminal B, through the back point of contact 37 of relay 5ATR, contact 38 of relay 5Afp, and the winding of relay 5ABP, with a resistor r connected in multiple with contact 38 of relay 5Afp and the winding of relay 5ABP, to terminal N. Relay 5ABP is also made slow releasing by resistor r connected in multiple with its winding, so that the front contacts of relay 5ABP remain closed during the intervals when contact 37 of relay 5ATR is open at the back point. Relays 6ATR, 6Afp, and 6ABP are energized similarly to relays 5ATR, 5Afp, and 5ABP. Each of the floating track relays 6ATR and 11ATR is energized by current of 180 code supplied to section 6T or 11T, respectively, by an associated battery 14 through the front point of a contact 18 of an associated code transmitter 183CT. Contact 37 of each of the relays 6ATR and 11ATR is therefore repeatedly closed alternately at its front and back points at a frequency of 180 times per minute. Relays 6Afp and 11Afp are energized similarly to relay 5Afp, and relays 6ABP and 11ABP are energized similarly to relay 5ABP.

Mechanism 2m of signal 2S is energized by current of normal polarity for retaining this mechanism in the clear position, through a circuit passing from terminal B, through the front point of contact 39 of relay 4HDP, contact 5ABP-40, contact 41 of relay 3TR, contact 42 of relay 2TR, mechanism 2m, and the front point of contact 45 of relay 4HDP to terminal N. Each of the mechanisms 3m, 8m, and 9m for signals 3S, 8S, and 9S, respectively, is energized similarly to mechanism 2m.

We shall assume that, with apparatus embodying our invention as shown in the accompanying drawings, thus in the normal condition, an eastbound train passes the next pair of head block signals west of signal 2S, causing signal 1S to indicate stop. With signal 1S indicating stop, contacts 15 and 16 of this signal are both open at their front points, and therefore relay 1HDP becomes deenergized.

With relay 1HDP deenergized, mechanism 3m

75

becomes energized by current of reverse polarity in a circuit which is the same as the circuit previously described for this mechanism except that it includes the back points of contacts 39 and 45 of relay 1HDP instead of the front points of these contacts. When mechanism 3m becomes energized by current of reverse polarity, contact 15 of signal 3S becomes opened at its front point and closed at its back point, and contact 16 of this signal becomes closed at its front point. With contact 15 of signal 3S opened at its front point, relay 3DP becomes deenergized, but relay 3HDP is now energized by a circuit passing from terminal B, through contact 15 of signal 3S closed at its back point, contact 16 of signal 3S closed at its front point, and winding of relay 3HDP to terminal N.

With relay 3DP deenergized, the circuit previously traced for relay 5CTP through contact 22 of this relay becomes opened, and a second circuit is now completed for relay 5CTP, passing from terminal B, through contact 19 of a code transmitter 120CT, front point of contact 21 of relay 3HDP, back point of contact 22 of relay 3DP, and the winding of relay 5CTP in multiple with a resistor t to terminal N. Relay 5CTP is therefore now energized by current of 120 code controlled by code transmitter 120CT.

Current of 120 code is therefore now supplied to section 5T through the front point of contact 5CTP-23. Relay 5TR is therefore energized by current of 120 code frequency received from section 5T, and hence relay 5DRB now becomes energized and relay 5DRA becomes deenergized, while relay 5HR remains energized as before except by current controlled by the 120 code frequency instead of by the 180 code frequency.

With relay 5DRA deenergized, mechanism 5m is now energized by current of reverse polarity in a circuit which is the same as the circuit previously traced for this mechanism except that it includes the back points of contacts 28 and 30 of relay 5DRA instead of the front points of these contacts.

With mechanism 5m thus operated to the caution position, the circuit previously described for relay 5HDP is opened at the front point of contact 15 of signal 5S, but relay 5HDP is now energized by a circuit passing from terminal B, through the back point of contact 15 of signal 5S, front point of contact 16 of signal 5S, and the winding of relay 5HDP to terminal N.

The circuit previously traced for relay 5PC is now open at contact 23 of relay 5DRA, but relay 5PC remains energized by a second circuit, passing from terminal B, through contact 27 of relay 5DRB, and the winding of relay 5PC to terminal N.

With relays 5HDP and 5PC thus energized, the circuit previously described for mechanism 7m is still closed, and therefore signal 7S continues to display the clear indication.

After the eastbound train has entered section 8T and has proceeded part way through this section, the floater track relay 6ATR adjacent signal 2S will become deenergized similarly to floater track relay 6ATR, the operation of which will be traced later. Relay 6ABP will therefore be deenergized, making effective the overlap control for signal 3S by deenergizing mechanism 3m at contact 40 of relay 6ABP.

With mechanism 3m thus operated to the stop position, both contacts 15 and 16 of signal 3S will be opened at their front points, and hence relay 3HDP as well as 3DP will be deenergized.

Relay 5CTP will therefore now be energized by current of the 75 code frequency passing from terminal B, through contact 20 of code transmitter 75CT, back point of contact 21 of relay 3HDP, back point of contact 22 of relay 3DP, and the winding of relay 5CTP in multiple with resistor t to terminal N. Current of the 75 code frequency will therefore now be supplied to section 5T through the front point of contact 5CTP-23, and relay 5TR will operate its contacts 24 and 25 at a frequency of 75 times per minute.

Relay 5HR will remain energized by current of this frequency, but relay 5DRB as well as relay 5DRA will be deenergized. With relay 5HR still energized, mechanism 5m of signal 5S will remain energized by current of reverse polarity for retaining signal 5S in the caution position.

With both relays 5DRB and 5DRA deenergized, relay 5PC will now also be deenergized, causing mechanism 7m to be energized by current of reverse polarity in a circuit which is the same as the circuit previously described for this mechanism except that it includes the back points of contacts 5PC-31 and 5PC-36 instead of the front points of these contacts. Signal 7S will therefore now indicate caution. The circuit by which relay 1HDP was previously energized through the front point of contact 15 will now be open, but relay 1HDP will now remain energized by a circuit through the back point of contact 15 and the front point of contact 16 of signal 7S.

Mechanism 9m of signal 9S will therefore remain energized by current of normal polarity. When the eastbound train enters section 2T, mechanism 2m will be deenergized because of the opening of contact 42 of relay 2TR. Signal 2S will therefore now display a stop indication. When the train enters section 3T, the circuits for mechanisms 2m and 3m will be opened at another point through contacts 41 and 44 of relay 3TR.

When the train leaves section 0T, relays 1HDP and 0ABP will become energized, but mechanism 3m will remain deenergized as long as the train occupies section 2T or 3T, because of contacts 43 and 44 of relays 2TR and 3TR, respectively, being open.

When the train enters section 5T, relay 5ATR will become deenergized, and therefore relays 5AAPP and 5ABP will also be deenergized. The circuit for mechanism 2m will therefore now be open at another point because of the opening of contact 5ABP-40.

Relay 5TR will also become deenergized when the train enters section 5T, and therefore relay 5HR will be deenergized and open the circuit for mechanism 5m, causing signal 5S to display a stop indication. With mechanism 5m in the stop position, relay 5HDP will become deenergized.

With relay 5HR deenergized, the circuit for mechanism 4m is open at contact 34 of relay 5HR, and hence mechanism 4m will move to the stop position, and relay 4HDP will become deenergized.

With relay 5HDP deenergized, the circuit for mechanism 7m will be open at contacts 5HDP-32 and 5HDP-35, and therefore mechanism 7m will be operated to the stop position.

Relay 1HDP will therefore be deenergized, so that mechanism 9m will be energized by current of reverse polarity and will be operated to the caution position.

When the train leaves section 3T, mechanism 7S

3m will become energized by its circuit first described, and therefore signal 3S will display the clear indication. The circuit for mechanism 2m will, however, still remain open, because relay 5ABP will remain deenergized until the train has proceeded part way through section 5T.

When the train enters section 6T, relay 6TR will become deenergized, but relay 6ATR will remain energized until the train has proceeded part way through section 6T. With relay 6TR deenergized, relay 6DRA and, in turn, also relay 6PC will be deenergized.

With relay 6HR also deenergized, on account of relay 6TR being deenergized, relay 6SR will become energized by a pickup circuit passing from terminal B, through the back point of contact 5SR-46, contact 47 of relay 6HR, front point of contact 48 of relay 6HDP, contact 5HDP-49, and the winding of relay 6SR to terminal N. Relay 6SR, upon becoming energized, completes a stick circuit which is the same as the pickup circuit just traced except that it includes contact 50 of relay 6SR, instead of contact 48 of relay 6HDP and contact 5HDP-49.

Relay 6HR, upon becoming deenergized, also opens the circuit for mechanism 6m, causing signal 6S to display the stop indication. With signal 6S indicating stop, relay 6HDP will become deenergized and complete a second stick circuit for relay 6SR, this circuit passing from terminal B, through the back point of contact 5SR-46, back point of contact 48 of relay 6HDP, contact 50 of relay 6SR, and the winding of relay 6SR to terminal N.

The circuit for mechanism 1m is now open at contact 34 of relay 6HR, but this circuit is already open at contact 5HDP-35. The circuit for mechanism 7m is now also opened at contact 33 of relay 6SR.

When the train has proceeded part way through section 5T, relay 5ATR will again become energized, and relays 5AAPP and 5ABP will again be energized by their circuits previously traced. With relay 5ABP again energized, the circuit for mechanism 2m will be energized by current of reverse polarity, including the back points of contacts 39 and 45 of relay 4HDP.

When the train has passed part way through section 6T, relay 6ATR will become deenergized, and hence relay 6ABP will also become deenergized and cause the mechanism of signal 9m to move to the stop position similarly to the manner previously described for mechanism 3m.

When the train leaves section 5T, relay 5TR will again become energized, causing relays 5HR and 5DRA to also in turn become energized. Mechanism 5m will therefore again become energized by current of normal polarity, causing signal 5S to display the clear indication. Relays 5HDP and 5PC will then become energized as previously described.

Mechanism 4m will now become energized by current of reverse polarity passing from terminal B, through the front point of contact 6SR-46, back point of contact 6HDP-35, contact 34 of relay 5HR, contact 33 of relay 5SR, mechanism 4m, and the back point of contact 6HDP-32 to terminal N. Signal 4S will therefore now display the caution indication, and relay 4HDP will again become energized and complete the circuit for again energizing the circuit for mechanism 2m by current of normal polarity.

Signal 2S will therefore now again display the clear indication.

As the train now proceeds further, the opera-

11

tion of the signals at siding W will be similar to that already described for the signals at siding X. When mechanism $8m$ becomes deenergized by the train on section $8T$, relays $8DP$ and $8HDP$ will become deenergized, and relay $6CTP$ will then become energized by coded current of the 75 frequency passing from terminal B, through contact 20 of code transmitter $15CT$, back point of contact 21 of relay $8HDP$, back point of contact 22 of relay $8DP$, and the winding of relay $6CTP$ in multiple with resistor t to terminal N.

When the train now leaves section $6T$, relay $6TR$ will therefore be energized by current of the 75 code, and hence relay $6HR$ will again be energized and mechanism $6m$ will be energized by current of reverse polarity in its circuit which now includes the back points of contacts 23 and 30 of relay $6DRA$ instead of the front points of these contacts. With signal $6S$ displaying the caution indication, relay $6HDP$ will become energized and open its contact 48 at the back point, thereby deenergizing relay $6SR$. Relay $6PC$ will still be deenergized, and therefore mechanism $4m$ will still remain in the caution position.

With relay $6HR$ again energized and relay $6SR$ deenergized, mechanism $7m$ will now be energized by current of normal polarity in its circuit first described.

As the train proceeds further after entering section $11T$, the floating track relay $11ATR$ for section $11T$ will become energized and cause relay $11ABP$ to again be energized. Mechanism $8m$ will then become energized by current of reverse polarity, and hence relay $8HDP$ will again become energized.

With relay $8HDP$ energized and relay $8DP$ deenergized, relay $6CTP$ will be energized by current of 120 code passing from terminal B, through contact 19 of a code transmitter $120CT$, front point of contact 21 of relay $8HDP$, back point of contact 22 of relay $8DP$, and the winding of relay $6CTP$ in multiple with a resistor t to terminal N. Relay $6TR$ will therefore now be energized by coded current of 120 frequency, and hence relays $6HR$ and $6DRB$ will again become energized.

With relay $6DRA$ now deenergized and relay $6HR$ energized, mechanism $6m$ will become energized by current of reverse polarity for operating signal $6S$ to the caution position.

With relay $6DRB$ energized, relay $6PC$ will also be energized, and therefore mechanism $4m$ will again become energized by current of normal polarity for controlling signal $4S$ to display the clear indication.

We shall now assume that all parts of the apparatus become again returned to the normal condition, and that a westbound train enters section $11T$ while an eastbound train is between signal $2S$ and signal $4S$ at siding X. Signal $4S$ will continue to display the clear indication until the westbound train arrives at a point at which the floating track relay $11ATR$ for section $11T$ releases and causes relay $11ABP$ to be deenergized.

When relay $11ABP$ becomes deenergized, mechanism $8m$ becomes deenergized by the opening of contact 40 of relay $11ABP$, and therefore signal $8S$ indicates stop. Relays $8HDP$ and $8DP$ will therefore be deenergized, and hence relay $6CTP$ will be energized by current of the 75 code.

Mechanism $6m$ will therefore be energized by current of reverse polarity, and hence signal $6S$ will display the caution indication.

Relay $6PC$ will be deenergized because both relays $6DRB$ and $6DRA$ are deenergized, and

12

therefore mechanism $4m$ will be energized by current of reverse polarity, and signal $4S$ will display the caution indication for the eastbound train.

With the eastbound train between signals $2S$ and $4S$, mechanism $3m$ will be deenergized, and therefore current of the 75 code will be supplied to section $5T$, and signal $7S$ will therefore display the caution indication for the westbound train.

We shall next assume that an eastbound train has just passed signal $6S$, and a westbound train has just passed the first intermediate signal east of signal $10S$. With both relays $6ABP$ and $11ABP$ energized, mechanisms $9m$ and $8m$ will be energized by current of reverse polarity, and therefore signals $8S$ and $9S$ will display the caution indication.

When the westbound train arrives at the point at which the floating track relay $11ATR$ for section $11T$ becomes deenergized, relay $11ABP$ will become deenergized, and hence signal $8S$ will display the stop indication for the eastbound train. When the eastbound train arrives at the point at which relay $6ATR$ becomes deenergized, relay $6ABP$ will also become deenergized, and therefore signal $9S$ will be controlled to display the stop indication for the westbound train.

We have described the operation of the apparatus for a few typical traffic movements. It is believed that, in view of this description, the operation of the apparatus for any other possible traffic movement can be readily understood by reference to the drawings.

Although we have herein shown and described only one form of apparatus embodying our invention, it is understood that various changes and modifications may be made therein within the scope of the appended claims without departing from the spirit and scope of our invention.

Having thus described our invention, what we claim is:

1. In a control system for signals for a stretch of single track railway including a first pair of signals adjacent a given end of said stretch and a second pair of signals adjacent the opposite end of said stretch, a given signal of each of said pairs arranged for governing traffic movements onto said stretch and the other signal of each of said pairs arranged for governing traffic movements off of said stretch, and including a pair of intermediate signals between said first and second pairs of signals one for governing traffic movements in a given direction over a first section of said track between said first pair of signals and said intermediate signals and the other for governing traffic movements in the opposite direction over a second section of said track between said second pair of signals and said intermediate signals, the combination comprising, means controlled in conjunction with each of said signals which governs traffic movements off of said stretch for supplying current of a first or a second or a third code to the adjacent said first or said second section according as the associated said signal for governing traffic movements off of said stretch is controlled to display a clear or a caution or a stop indication respectively, means controlled by the track circuit for each of said sections when energized by current of said first code for controlling the associated intermediate signal to display a clear indication, means controlled by the track circuit for each of said sections when energized by current of said second code or said third code for controlling the associated

intermediate signal to display a caution indication, and a line circuit for each of said given signals controlled by said coded track circuits for controlling its signal to display a clear indication if the adjacent track circuit is supplied with current of any one of said three codes while the other track circuit is supplied with current of said first or second codes and for controlling its signal to display a caution indication if the adjacent track circuit is supplied with current of any one of said three codes while the other track circuit is deenergized by a train moving toward the other given signal or is supplied with current of said third code.

2. In a control system for railway signals for a stretch of single track railway which is provided with passing sidings spaced along the single track, including two pairs of head block signals for each passing siding each comprising an entering and a leaving signal one pair adjacent each end of its passing siding for governing traffic movements in opposite directions, including a pair of intermediate signals between each two consecutive passing sidings for governing traffic movements in opposite directions, the combination comprising, two non-coded track circuits between the two pairs of head block signals for each passing siding, two coded track circuits between each two consecutive passing sidings one between each of the passing sidings and the associated pair of intermediate signals, two traffic controlled line circuits between the two pairs of head block signals at each passing siding, a traffic controlled line circuit between each pair of intermediate signals and the next pair of head block signals in each direction, and means controlled by said track circuits and by said line circuits for controlling said head block and intermediate signals including overlapping clear control means for each two opposing leaving head block signals.

3. In a control system for railway signals for a stretch of single track railway which is provided with passing sidings spaced along the single track, including two pairs of head block signals for each passing siding each comprising an entering and a leaving signal one pair adjacent each end of its passing siding for governing traffic movements in opposite directions, including a pair of intermediate signals between each two consecutive passing sidings for governing traffic movements in opposite directions, the combination comprising, two non-coded track circuits between the two pairs of head block signals for each passing siding, two coded track circuits between each two consecutive passing sidings one between each of the passing sidings and the associated pair of intermediate signals, traffic controlled line circuit means including four line conductors between the two pairs of head block signals at each passing siding and two line conductors between each pair of intermediate signals and the next pair of head block signals in each direction, and means controlled by said track circuits and by said line circuit means for controlling said head block and intermediate signals including overlapping clear controls for each two opposing leaving head block signals.

4. In a control system for railway signals for a stretch of single track railway which is provided with passing sidings spaced along the single track, including two pairs of head block signals for each passing siding each comprising an entering and a leaving signal one pair adjacent each end of its passing siding for governing traffic

movements in opposite directions, including a pair of intermediate signals between each two consecutive passing sidings for governing traffic movements in opposite directions, the combination comprising, control means for each of said entering signals controlled by traffic conditions between its entering signal and the next leaving signal in advance and by pole changing means operated in conjunction with the next leaving signal in advance, means controlled in conjunction with each entering signal for supplying current of a first code or a second code or a third code to a track circuit between the entering signal and the next intermediate signal in the rear according as the entering signal is controlled to display a clear or a caution or a stop indication respectively, means for controlling each of said intermediate signals by the coded track circuit over which it governs traffic movements to display a clear indication if its track circuit is energized by current of said first code and to display a caution indication if its track circuit is energized by current of said second or said third code, means for controlling each of said leaving signals to display a clear indication if the track is unoccupied between the leaving signal and the next intermediate signal and if the next intermediate signal which governs traffic movements in the same direction is controlled to display either a clear or a caution indication while current of either said first or said second code is being supplied to said track between said next intermediate signal and the next opposing leaving signal, and means for controlling each of said leaving signals to display a caution indication if the track is unoccupied between the leaving signal and said next intermediate signal and if current of said third code is being supplied to the track between said next intermediate signal and said next opposing leaving signal.

5. In a control system for railway signals for a stretch of single track railway which is provided with passing sidings spaced along the single track, including two pairs of head block signals for each passing siding each comprising an entering and a leaving signal one pair adjacent each end of its passing siding for governing traffic movements in opposite directions, including a pair of intermediate signals between each two consecutive passing sidings for governing traffic movements in opposite directions and including a first section of said track between each pair of intermediate signals and the next pair of head block signals in a given direction from said intermediate signals and a second section of said track between each pair of intermediate signals and the next pair of head block signals in the opposite direction from said intermediate signals, the combination comprising, means controlled in conjunction with each entering signal for supplying current of a first or a second or a third code to the adjacent end of the adjacent said first or second track section according as the entering signal is controlled to display a clear or a caution or a stop indication respectively, a floating track relay connected adjacent each leaving signal across the adjacent said first or second track section, control means for each of said entering signals controlled by traffic conditions between the entering signal and the next leaving signal in advance and by the floating track relay which is adjacent the next leaving signal in advance and also by pole-changing means operated in conjunction with the next leaving signal in advance, means for controlling each of said in-

termediate signals by current of said first code received from the section over which it governs traffic movements to display a clear indication and by current of said second or third code received from the same section to display a caution indication, and means for controlling each of said leaving signals if the first track section in advance is unoccupied to display a clear indication if current of said first or said second code is received from the second section in advance and to display a caution indication if current of said third code is received from the second section in advance.

6. In a control system for railway signals for a stretch of single track railway which is provided with passing sidings spaced along the single track, including two pairs of head block signals for each passing siding each comprising an entering and a leaving signal one pair adjacent each end of its passing siding for governing traffic movements in opposite direction, including a pair of intermediate signals between each two consecutive passing sidings for governing traffic movements in opposite directions, and including a first section of said track between each pair of intermediate signals and the next pair of head block signals in a given direction from said intermediate signals and a second section of said track between each pair of intermediate signals and the next pair of head block signals in the opposite direction from said intermediate signals, the combination comprising, means controlled in conjunction with each entering signal for supplying current of a first or a second or a third code to the adjacent end of the adjacent said first or second track section according as the entering signal is controlled to display a clear or a caution or a stop indication respectively, means for controlling each of said entering signals according to traffic conditions in advance, means for controlling each of said intermediate signals by current of said first code received from the section over which it governs traffic movements to display a clear indication and by current of said second or said third code received from the same section to display a caution indication, and means for controlling each of said leaving signals if the first track section in advance is unoccupied to display a clear indication if current of said first or said second code is received from the second section in advance and to display a caution indication if current of said third code is received from the second section in advance.

7. In a control system for railway signals for a stretch of single track railway which is provided with passing sidings spaced along the single track, including two pairs of head block signals for each passing siding each comprising an entering and a leaving signal one pair adjacent each end of its passing siding for governing traffic movements in opposite directions, including a pair of intermediate signals between each two consecutive passing sidings for governing traffic movements in opposite directions, and including a first section of said track between each pair of intermediate signals and the next pair of head block signals in a given direction from said intermediate signals and a second section of said track between each pair of intermediate signals and the next pair of head block signals in the opposite direction from said intermediate signals, the combination comprising, means controlled in conjunction with each entering signal for supplying current of a first or a second or a third code to the adjacent end of the adjacent said first or second track section according as the entering signal is controlled to display a clear or a caution or a stop indication respectively, means for controlling each of said entering signals according to traffic conditions in advance, means for controlling each of said intermediate signals by current of said first code received from the section over which it governs traffic movements to display a clear indication and by current of said second or third code received from the same section to display a caution indication, means including current of said first or said second code received from the second section in advance for controlling each of said leaving signals to display a clear indication, and means including current of said third code received from the second section in advance for controlling each of said leaving signals to display a caution indication.
